UNITED STATES PATENT OFFICE.

PAUL RAYMOND SIMMONS, OF MARION, INDIANA.

DISH-FORMING MACHINE.

1,147,759.

Specification of Letters Patent. Patented July 27, 1915.

Application filed August 2, 1913. Serial No. 782,669.

To all whom it may concern:

Be it known that I, PAUL R. SIMMONS, a citizen of the United States, and a resident of Marion, in the county of Grant and State 5 of Indiana, have invented certain new and useful Improvements in Dish-Forming Machines, of which the following is a specification.

My present invention relates to an improved machine for forming paper dishes or pie-plates and more particularly to a machine of this character which is adapted to be used in connection with a rotary cutting device and to receive the paper therefrom, 15 such a cutting device as described and claimed in my Patent No. 1,044,931, dated November 19, 1912.

The primary object of this invention is to provide a machine which will automatically 20 accept and press into the form of dishes or pie plates, paper disks partially cut out of a strip web or sheet of paper or pulp stock in a moist, or somewhat "green" state, and which will at the same time cure the paper 25 and dispose of or discharge the waste paper. These objects, and certain others which will be apparent, with their resulting advantages, I attain by means of the structure to be now described with reference to the accompanying drawing, in which,

Figure 1 is a vertical transverse sectional view taken substantially on line 1—1 of Fig. 2. Fig. 2 is a vertical longitudinal sectional view taken substantially on line 2—2 of Fig. 1. Fig. 3 is a horizontal section taken substantially on line 3—3 of Fig. 1. Fig. 4 is a side elevation of the complete apparatus. Fig. 5 is a plan view of a portion of the partially cut web or 40 sheet, and, Fig. 6 is a sectional detail of one of the waste breaking plungers.

Referring now to these figures, the frame A of my improved machine embodies a substantially U-shaped upper portion and a 45 base upon the forward portion of which is formed a shelf adapted, as clearly shown in Fig. 2 to support the cutting device. This cutting device being fully described in my patent above referred to, it will suffice here 50 to say that it embodies superposed rollers, one of which is provided with circular cutting edges on its periphery so that by proper relative adjustment of the rollers, a sheet or web of paper fed therebetween, may be partially cut up into disks. This cutting device is shown in dotted lines in Figs. 2 and 4

and the web B, partially cut and before being pressed to shape, is shown in detail in Fig. 5.

From the cutting machine, the web B is 60 automatically fed into the forming machine above the skeleton bed plate C and the female dies C' supported thereon and in passing thereover is subject to the combined action of these female dies C' and the male 65 dies D and also to the action of the waste-breaking plungers.

The dies C' and D are hollow as particularly shown in Fig. 1 and centrally braced, the female dies C' having central spring-controlled plungers c by which the plates when formed are lifted and may thus be discharged by succeeding portions of the web B. These hollow dies receive a constant supply of steam or other heating 70 agent through pipes F and F', the latter, which communicates with the male dies being flexible in order to allow for the necessary movement of these dies.

The upwardly extending cylindrical stems 80 D' of the male dies are journaled through bearings g in a guide frame G rigidly connected between the side portions of the frame A, the upper ends of these stems receiving the lower ends of the rods h depending from the carriage H, the latter sliding on the frame ribs a under actuation of the pitmen i extending from the cranks i' of the crank shaft I. The stems D' have transverse slots through which extend pins 90 h' carried by rods h, the lower ends of the latter bearing on springs d within the stems whereby to form a cushion.

The waste-breaking plungers are in the form of spring-controlled rods j, the lower 95 heads J of which are generally triangular and of the particular shape shown in Fig. 6, these rods extending through bearing tubes g' in the guide frame G and having their upper angular extremities j' adapted to be 100 engaged by angularly extending members k of arms K depending from the carriage H, when the carriage moves upwardly in order to raise the waste-breaking plungers and put their springs j' under tension. The 105 plungers are held in an upper position by triggers j'' which the members k engage and release upon the downward movement of carriage H whereby the plungers are free to descend under actuation of their springs 110 and break out the triangular portions b' of the web B between the disks b at the

time the latter are clamped between the dies and pressed into shape as shown in Fig. 3.

One outer end of the crank shaft I is provided with a gear wheel I' which is connected to the driving gear L through an intermediate gear L', the latter also transmitting power to the cutting device whereby the web B may be properly fed and the two operations relatively timed. It will thus be seen that as the power is applied, the partially cut web of paper or pulp stock in a moist or somewhat "green" state will be automatically fed from the cutting device between the forming dies and that the carriage will lower to clamp and form the partially cut disks between the dies, at which time the plungers J will be tripped and allowed to descend, breaking out the waste material between the disks and discharging the same downwardly between the female dies. When the carriage H rises the formed plates as shown in Fig. 3 will be thrust upwardly by the plungers c and discharged by the oncoming web B. It will be further seen that during the forming operation between the dies, and by virtue of the fact that these dies are supplied with sufficient and constant heat through the means before described, the plates will be cured and thus their shape will be preserved.

I claim:

1. In a paper plate forming machine, the combination of means for feeding a sheet of partially cut disks, means for stamping out and curing the plates, and means for stamping out the waste material between the several plate disks.
2. In a paper plate forming machine, the combination of sheet feeding means, dies for stamping circular formed plates therefrom, and waste breaking plungers to stamp out waste material from between the plates, movable with respect to the dies when the latter are in clamped positions on the plates.
3. In a paper plate forming machine, dies

for stamping circular formed plates from a sheet, a frame in which certain of the dies are supported, a carriage slideable in the frame for moving others of the dies, waste breaking plungers mounted in the frame, means for moving the plungers with respect to the dies movable with the carriage, and means actuated by the carriage for controlling movement of the said plungers.

4. In a paper plate forming machine, the combination of means for feeding a sheet of partially cut disks, sets of opposing dies for clamping the sheet between them and shaping the disks, and spring actuated plungers controlled by movement of the dies and movable against the sheet when the dies are clamped thereon to stamp out the waste material between the disks, all substantially as described.

5. The combination of male and female dies for pressing paper to form plates, a frame in which the female dies are supported, a carriage slideable in the frame for moving the male dies, spring-actuated plungers mounted in the frame to stamp out the waste material between the plates, and means movable with the carriage for controlling said plungers.

6. In a paper plate forming machine, the combination of means for feeding a sheet of partially cut disks, hollow dies for stamping out and curing the disks, means for supplying the said dies with a heating fluid, and means for stamping out the waste material between the several plate disks.

7. In a paper plate forming machine, the combination of means for feeding a sheet of partially cut disks, and reciprocating plungers for stamping out and curing the plates and stamping out the waste material between the several plate disks.

PAUL RAYMOND SIMMONS.
